UNITED STATES PATENT OFFICE.

DOMENICO GUARINO, OF NEW YORK, N. Y.

CAR-FENDER.

SPECIFICATION forming part of Letters Patent No. 644,596, dated March 6, 1900.

Application filed July 5, 1899. Serial No. 722,884. (No model.)

To all whom it may concern:

Be it known that I, DOMENICO GUARINO, a subject of the King of Italy, and a resident of New York city, county of New York, and 5 State of New York, have invented certain new and useful Improvements in Car-Fenders, of which the following is a specification, reference being had to the accompanying drawings, forming a part thereof, in which similar 10 letters of reference indicate corresponding parts.

My invention relates to an improvement in car-fenders, and has for its object to provide a cheap and effective fender by the use of 15 which a body upon being struck by a car is taken up in the fender and the car is prevented from passing over the body. I attain this object by the device illustrated in the accompanying drawings, in which—

20 Figure 1 is a general side view, and Fig. 2 is a top view omitting the lower fender. Fig. 3 is a view of my device in operation with a body held therein. The lower portion or part of my device directly beneath the car is not 25 shown in this view.

My device is attached to the front end of a street-car and in construction consists of a frame A, pivotally fastened to the under side of car A' at a. The front end of the frame 30 A is movably carried upon the rod A² and has depending from it a secondary frame A³, which carries the arms a' and a², which in turn carry a frame G, which carries upon its forward end a scoop H, pivotally fastened to the front 35 end of the frame G. The frame G is braced by the arm G', which is rigidly fastened to the frame A³ and is pivotally connected to the car at g, concentric with the fastening a of the frame A. A guiding-arm g' is pivotally fastened at g² to the frame G and is employed to guide the fender around curves when the underground conduit system is used, the said guiding-arm g' working in the slot of the conduit. A small roller h' may be 45 mounted upon the frame A³ and run in the slot and may also be employed as a guide for the fender in turning curves.

The scoop H extends the full width of the track and is provided with the arms h, pivotally fastened to the frame G and spaced about 50 twelve inches apart.

Where the conduit system is not in use, the

roller h' may be extended to each side and engage in the track.

The frame A is extended to form the side 55 pieces or frame B, which is turn carries the frame C, hinged thereto at c.

A frame D is pivotally fastened at d to the frame C and has the upright arms d', extending upwardly from it, and pivotally fastened to the said upright arms d' at d² are the frames E and E'. An arm F, formed with a tooth f, is pivotally fastened to the frame or side piece B and is weighted at its lower end f'. The tooth f is adapted to engage and 60 hold in position the frame D.

Pivotally fastened to the frame E is an arm e, which is adapted to engage the ratchet-teeth e' upon the frame E' when the frame E has swung around to its lowest position, thereby locking the said frame.

The device operates as follows: When the car is in motion and a person is standing in the path of the car, the lower portion e⁵ of the frame E² will strike the body and the impact will force back the said frame E². This frame revolves about d² and moves the upper frame E forward by means of the lug e⁴ until it falls forward and downward, catching the body, as shown by dotted lines in Fig. 3. The 75 frame E' is provided with a suitable netting about half the distance to the joint d². The impact of the body against the fender acts to throw or swing the frames E and E' back until they strike the arm F, which, being 80 pivoted, swings back until the tooth f disengages the frame D, thereby allowing it to drop and swing about on e². The arm e engaging in the ratchet-pieces e' acts to lock the frames E and E', thereby securely holding 85 the body within the fender. The lower portion of the fender embodying the scoop acts in case the body is not caught by the larger fender and falls to the track, whereupon the scoop H will strike it, and the impact will 90 cause the scoop H to be forced back and down and scoop up the body, which will slide under the arms h and be held upon the scoop by the same. The dotted lines in Fig. 1 show the 95 position of the scoop when forced back by 100 impact of the body.

The framework of the fender is so constructed as to allow its being folded back against the dashboard of the car, thereby al-

lowing the car to be pushed by a second car engaging against the bumper k , the chain attached to said bumper k being employed to fasten the two cars together when it is desired to have the second car draw the first one.

The upper framework of the fender may be entirely omitted and the lower portion or scoop employed effectively. The body upon being struck throws back the scoop portion, and the arms h^2 being lowered engage with the upright lugs in the ground and acts to instantly bring the car to a stop. When the scoop and frame are thrown backward, the rod or arm g' acts to cut off the electric current, thereby preventing the motors of the car from operating.

Having thus described my invention, what I claim as new, and desire to secure by Letters Patent, is—

The combination, in a fender for street-cars, of collapsible frames, a frame beneath the car and pivotally connected to the car, said frame carrying the collapsible frames, a movable frame fastened to the lower portion of the frame under the car, a scoop carried upon the movable frame, a guiding-roller for guiding the fender around curves, and lugs located upon the surface of the ground and adapted to bring the car to a standstill instantaneously when the scoop is in lowered position, substantially as described.

In testimony that I claim the foregoing as my invention I have signed my name, in presence of two witnesses, this 30th day of June, 1899.

DOMENICO GUARINO.
